ROBERT N. EAGLE, OF WASHINGTON, DISTRICT OF COLUMBIA.

Letters Patent No. 98,937, dated January 18, 1870.

IMPROVEMENT IN LAMP-CHIMNEYS.

The Schedule referred to in these Letters Patent and making part of the same.

To all whom it may concern:

Be it known that I, ROBERT N. EAGLE, of Washington, in the District of Columbia, have invented new and useful Improvements in Lamp-Chimneys; and I do hereby declare that the following is a full, clear, and exact description of the same, reference being had to the annexed drawing, making part of this specification, in which—

Figure 1 is a side elevation of a chimney.

Figure 2 is a section on the line $x-x$ of fig. 1.

Figure 3 is a section on the line $y-y$ of fig. 1.

Figure 4 is a vertical section on the line $z-z$ of fig. 1.

Figures 5, 6, 7, and 8, are corresponding views and sections of another chimney, slightly modified in form, and having a reflector attached to the surface of the chimney.

The same letters in all the figures indicate identical parts.

My improved chimney is especially adapted for use on the various kinds of lamps burning the kerosene-oils, &c; and

My invention consists in several peculiarities of form to be hereinafter specifically indicated, intended to produce a more intense combustion, and, at the same time, diminish the danger of fracture by the action of the heat of the flame; also, in the manner of attaching, to the surface of the chimney, a reflector upon one side, to increase the amount of light thrown upon an object.

In the annexed drawings, I have represented a chimney especially designed for use upon burners of the class properly known as the sun or comet-burners, and other burners of analogous construction.

A is the base, which rests upon the chimney-holder of the burner, and is designed to fit the deflecting-plate of such burners.

The throat is formed by the convergence of the sides, as clearly shown in the drawings, and it may be elliptical or elongated, as shown at B in figs. 6 and 7, but I prefer to widen it upon the sides of the throat, as clearly shown in figs. 2 and 3, at $b-b$, to allow a greater current of air to ascend at the sides of the flame.

Recesses are formed on the inside of the chimney, at $a-a$, at opposite points, and in line with the flat flame, which are designed to receive spring-points attached to the burner, to hold the chimney in proper position on the burner, and to serve as guides in so attaching the chimney, as to insure its proper position in relation to the flame.

The lower portion of the chimney I will designate as the flame or combustion-chamber, as it is intended to enclose the flame. It is flattened, the sides being nearly vertical and parallel, as shown in fig. 8, or slightly convex, as shown in fig. 4. The edges are curved outward, as shown in figs. 1 and 5, forming pockets at $c-c$, which are designed, by presenting a body of comparatively inert air, to protect the chimney against the

action of the upper corners of the flame, as the circulation of the air through these pockets will be impeded.

The upper portion of the chimney I will designate as the air-chamber; it is indicated by the letter D, in the drawings. This air-chamber begins at or near the upper edge of the flame, and lies above the flame. It is formed by curving the sides outwardly from the top of the flame-chamber C, so as to make the bulkiest part of the chimney entirely above the flame.

The diameter of the elliptical body of the chimney is increased both on the conjugate and transverse axis, but the greatest increase is in the length of the transverse axis, as will be seen by comparing figs. 1 and 5 with figs. 4 and 8. The effect of this increase is to reverse the form of the ordinary flattened chimney, and to give it the appearance of being turned upside down. The purpose of this enlargement above is to relieve the chimney from the effect of the heat, by retiring the portions of the glass most directly exposed to the action of the ascending current, and thereby avoiding that irregularity of expansion which is the most frequent cause of cracking.

The sides of the chimney form a regular curve, presenting a convex figure on the outside, from C' to D', and extending from the throat to the top of the air-chamber, as shown in fig. 4, or extending from the top of the flame-chamber C to the top of the air-chamber D, as shown in fig. 8.

The air-chamber, converging as it ascends, is terminated with a neck, E, which I shall denominate a super-gallery. This super-gallery is intended partly to increase the intensity of the draught, and partly to facilitate the blowing of chimneys having an elliptical mouth; I having found, by experience, that such chimneys are much more easily blown with, than without this super-gallery. The form of this portion of the chimney may be varied; it may be made with sides either vertical, concave, or convex.

Another improvement consists in the manner of attaching the reflecting-material directly to the surface of the chimney, and upon one side, so as to throw a stronger light upon any object placed in front of the open side. For this purpose I prefer to use silver-leaf, which may be attached to the exterior face of the chimney, immediately opposite to the flame, and covering a larger or smaller surface, as required. This leaf may be attached by means of size or "French gelatine," and, when dry, it may be overlaid with one or a succession of layers of silver-leaf or tin-foil, similarly superimposed, and then the whole covered by a coating of fire-proof paint or lacquer. I use, for this purpose, what is known as the water-proof enamel chemical paint, manufactured under the patent of Robert Levi, of September 8, A. D. 1868, and have found that it answers quite well.

I do not, however, claim all forms of reflectors, for

the surface of the glass itself, in many chimneys, operates to reflect rays of light; also reflectors of various materials, such as metal, glass, &c., are in common use, which are applied or secured by various means to the lamp; nor do I claim, broadly, for reflecting-substances attached in any manner to the surface of glass globes, shades, or chimneys, for I am aware that applications have heretofore been made for Letters Patent, in some of which a film of silver-leaf is spoken of as being attached to the surface of globes or shades, by a coating of a refractory paint or varnish, but no particular composition has been indicated as fitted for this purpose. A film of silver-leaf might be sufficiently protected by a composition to withstand the low heat of a globe, which would be entirely inadequate for protecting it upon a chimney, and particularly a flat or elliptical chimney, such as I propose to use, in which the metallic leaf is brought into very close proximity to the flame of the lamp; and I know of no case in which such a film has been attached to a chimney by a coating of paint or lacquer, sufficiently refractory to sustain the heat of the flat-wick lamps for burning kerosene, &c., in common use. I have, however, ascertained, by a long course of experiments, that the substance hereinbefore mentioned, possesses the peculiar combination of properties required, both for sustaining the high degree of heat, and for protecting the film of foil from being rubbed off or affected by the water used in washing the chimney.

What I claim as my invention, and desire to secure by Letters Patent, is—

1. A lamp-chimney, with recesses *a a* formed in the base of the chimney, in a line with the flat flame of the lamp, to serve as a guide in attaching the chimney, and for the purpose of receiving spring-points to

be attached to some permanent part of the burner, to secure the proper position of a flat chimney in relation to the flame, substantially as set forth.

2. A lamp-chimney, having its elliptical throat *B* widened in the line of its conjugate diameter, in the manner shown at *b b* in figs. 2 and 3, and substantially as set forth.

3. A lamp-chimney, constructed with pockets *c c*, recessed at points opposite the upper corners of the flame, substantially as set forth.

4. A lamp-chimney, the body of which is formed with a flame-chamber, *C*, and a superimposed enlarged air-chamber, *D*, substantially as set forth.

5. A lamp-chimney, combining, in its construction, a cylindrical base, a flattened and vertically-elongated body, contracted above, and concluding with an elliptical extension, *E*, forming the mouth, substantially as set forth.

6. A glass lamp-chimney, having attached to its exterior surface a thin film of foil of reflecting-metal, protected by an exterior coating of the said refractory compound, substantially as set forth.

7. A lamp-chimney, combining in its construction, the following elements, viz, a cylindrical base, an elliptical elongated body, an elliptical mouth, and a reflecting-surface of a metallic film, protected by refractory paint, substantially as set forth.

In testimony whereof, I have signed my name, to this specification, in the presence of two subscribing witnesses.

R. N. EAGLE.
